UNITED STATES PATENT OFFICE.

ERIK J. FRISK, OF WAUKEGAN, ILLINOIS.

RAILROAD-SPIKE.

1,354,737.

Specification of Letters Patent.

Patented Oct. 5, 1920.

Application filed June 19, 1918. Serial No. 240,773.

To all whom it may concern:

Be it known that I, ERIK J. FRISK, a citizen of the United States, residing at Waukegan, in the county of Lake and State of Illinois, have invented certain new and useful Improvements in Railroad-Spikes, of which the following is a specification.

This invention relates to improvements in railroad spikes, and more particularly to a type of spike adapted for use at railway crossings, at or near switch points and other places where the rails of one track cross or converge toward those of another track.

With the foregoing and other objects in view the invention consists in the combination and arrangement of parts to be herein-after fully described, pointed out in the appended claim and illustrated in the accompanying drawing which forms a part of this specification and in which—

Figure 1 is a view of my improved spike in side elevation.

Fig. 2 is an end view of Fig. 1.

Fig. 3 is a top plan view of Fig. 1.

Like reference characters denote corresponding parts throughout.

My improved spike comprises a pair of twin spaced legs 1, 2 which are formed at their free ends with the beveled portions 3, 30 said portions being formed upon the relatively remote faces of the legs, the adjacent faces thereof being straight and plain. The

legs 1, 2 are connected by the web 4 which is thickened and widened immediately above the said legs to form the heads 5 which taper off into the free ends 6.

The spikes are used chiefly adjacent rail intersections where they can be so driven into the tie that the tapered ends 6 of the heads 5 will engage the flanges of two rails. 40 Such points are found at crossings and where a siding branches off from the main line, etc. The legs 1, 2 web 4, heads 5 and head ends 6 are all integral thus cheapening the manufacture and economizing in material.

What is claimed is:—

In a railroad spike, twin spaced legs having their relatively remote faces beveled adjacent their ends and their adjacent faces flat and parallel, and a web connecting said legs, the ends of said web being tapered and extending substantially beyond the legs in the longitudinal plane of the web, said web at its points of juncture with the legs being thickened to form heads.

In testimony that I claim the foregoing as my own I have hereto affixed my signature in the presence of two subscribing witnesses.

ERIK J. FRISK.
